UNITED STATES PATENT OFFICE.

GEORGE MERKEL, OF PHILADELPHIA, PENNSYLVANIA.

GRATING-MACHINE.

SPECIFICATION forming part of Letters Patent No. 651,468, dated June 12, 1900.

Application filed May 1, 1897. Serial No. 634,731. (No model.)

To all whom it may concern:

Be it known that I, GEORGE MERKEL, a citizen of the United States, residing at Philadelphia, in the county of Philadelphia and 5 State of Pennsylvania, have invented certain new and useful Improvements in Grating-Machines, of which the following is a specification, reference being had therein to the accompanying drawings.

10 My invention relates to certain improvements in machines for grating cocoanut, and has for its object to provide a simple and economical form of machine which will effectually accomplish its purpose, as more fully 15 set forth hereinafter.

In the accompanying drawings, Figure 1 is a perspective view of a cocoanut-grating machine constructed in accordance with my invention. Fig. 2 is a sectional elevation of a 20 portion of the same on an enlarged scale. Fig. 3 is a perspective view of one of the grating-bars detached; and Fig. 4 is a sectional elevation of the machine, illustrating a modified form of grating-disk.

25 Referring to the drawings, A represents a supporting-table formed of a main fixed section *a* and a hinged section *a'*, the adjacent edges of each section being cut away to form an opening *b* for the passage of the grating- 30 disk. The section *a'* is hinged at *c* and may be locked to the main section by a thumb-screw *d* or other suitable device. The table is supported on legs or on a receptacle for the grated cocoanut and carries a bearing *e*, 35 in which is mounted a horizontal shaft *G* at some distance above the top of the table.

On the shaft *G* is mounted a grating-disk *H*, having grating or cutting teeth of any suitable character, the disk being held in 40 place by a nut *h* and being readily removed when it is necessary to substitute a disk having teeth of a different character. Thus in Fig. 1 the disk has radial slots *i* through which project teeth *h* on a bar *K*, and in Fig. 4 the 45 teeth are punched in a disk of sheet metal *H'*, as shown. Either of these disks or a disk having teeth of different character may be readily placed on the shaft when required.

The bars *K* are formed of flat metallic strips

provided at one edge with a series of slots *k'*, 50 cut through the bar at less than a right angle to its face and forming a series of teeth *k*, each having a sharp edge on each side, as shown more clearly in Fig. 3, so that they will cut in either direction and the disk may 55 be revolved to the right or to the left. The thickness of the strip in relation to the width of the slots and teeth is such that when the cutter-bar is lying flat and observed at a right angle to the plane of the bar the bar will appear as a solid piece of metal, there being apparently no space between the teeth, and it will in effect be practically a solid blade, so as to remove all of the face of the material being grated without leaving ridges between 60 the path of the teeth.

Usually the disk is revolved to the right, as indicated by the arrows in Figs. 1 and 2, as this gives the teeth a better chance to act; but when pieces of cocoanut too small to be 70 handled are to be grated the disk is revolved in the opposite direction and the pieces to be ground are placed in a small hopper *M*. This hopper, which is removable, is curved to conform to the disk and has an inner presser- 75 plate *m*, which is normally acted upon by a spring-pressed adjustable bolt to force the small pieces into contact with the teeth. The lower edge of the presser-plate has teeth *m'*, which prevent movement or shifting of the 80 particles of cocoanut.

Having thus described my invention, what I claim, and desire to secure by Letters Patent, is—

1. A grating-bar for cocoanut-grating machines formed of a flat metallic strip grooved or slit at one side to form a series of teeth, said grooves being inclined at less than a right angle to the plane of the strip so that said teeth will present a sharp edge on one 90 side only, substantially as specified.

2. A grating-bar formed of a flat metallic strip having on its cutting edge a series of spaced teeth separated by inclined grooves so arranged with respect to the bar that the cutting edge will be in effect a solid blade.

3. A grating-bar formed of a flat metallic strip having its edges at a right angle to the

plane of the strip there being in one edge of
said strip a series of slots inclined at less
than a right angle to the plane of the strip
so that on each edge of the strip the teeth
5 will present to the material to be grated one
sharp and one blunt edge substantially as
specified.

In testimony whereof I affix my signature
in the presence of two witnesses.

GEO. MERKEL.
